(57) **CLAIM**

The ornamental design for a hinged jewelry connector, as shown and described.

DESCRIPTION

FIG. 1 is a perspective view of a hinged jewelry connector with the hinged portion in a closed position showing the new design;

FIG. 2 is a perspective view thereof with the hinged portion in an open position;

FIG. 3 is a left side view thereof with the hinged portion in the closed position, with the right side view with the hinged portion in the closed position being a mirror image;

FIG. 4 is a left side view thereof with the hinged portion in an open position, with the right side view with the hinged portion in the same open position being a mirror image;

FIG. 5 is a front view thereof;

FIG. 6 is a back view thereof;

FIG. 7 is a top view thereof with the hinged portion in the closed position;

FIG. 8 is a bottom view thereof with the hinged portion in the closed position; and,

FIG. 9 is a perspective view thereof with the hinged portion in the closed position shown connecting two pieces of an earring.

The broken lines shown in FIG. 9 represent environmental subject matter only and form no part of the claimed design.

1 Claim, 4 Drawing Sheets
